UNITED STATES PATENT OFFICE.

GARDINER W. CHIPLEY, OF LOS ANGELES, CALIFORNIA.

INTERLOCKING BRAKE-SHOE.

1,144,639.

Specification of Letters Patent. Patented June 29, 1915.

Application filed August 5, 1914. Serial No. 855,130.

To all whom it may concern:

Be it known that I, GARDINER W. CHIPLEY, a citizen of the United States, and a resident of Los Angeles, in the county of Los Angeles and State of California, have made and invented certain new and useful Improvements in Interlocking Brake-Shoes, of which the following is a specification.

My invention relates to an improvement 10 in brake shoes, and more particularly to that kind or type thereof usually known and referred to as an interlocking shoe, that is, a shoe provided with means on the back of one shoe to engage with those provided 15 on the face of another whereby to secure the two shoes together, so that there may be secured a partially worn shoe to the face of an unworn shoe, and the partially worn shoe completely worn away in service.

20 The object of my invention is to provide a shoe of this character wherein the two shoes may be securely and positively locked together, and at a sufficient number of places throughout their length to overcome any 25 and all danger of separation should the partially worn shoe become cracked or broken.

A further object of the invention is to provide such fastening means as will permit the two shoes to be quickly locked together, which shall be inexpensive to manufacture, and efficient in use, and with these 30 and other ends in view consists in certain novel features of construction and combinations of parts as will be hereinafter fully 35 described and pointed out in the claims.

In the accompanying drawings, Figure 1 is a view in side elevation of an interlocking shoe constructed in accordance with my invention, the two shoes being secured together and having one end of each partially broken away in order to more clearly illustrate the method of attachment, the interlocking shoe being secured to a brake head in the ordinary manner, this view being 40 taken on the line 1—1 of Fig. 2 after the brake head has been attached. Fig. 2 is a plan view of the shoe, the brake head being removed. Fig. 3 is a bottom plan view of the same. Fig. 4 is a cross-sectional view 45 taken on the line 4—4 of Fig. 1, looking in the direction as indicated by the arrow. Fig. 5 is a sectional view taken on the line 5—5 of Fig. 1 looking in the direction as indicated by the arrow. Fig. 6 is a similar 50 view taken on the line 6—6 of Fig. 1 looking in the direction as indicated by the arrow.

The interlocking shoe, as a whole, comprises two shoes secured together, 7 representing the one shoe, and 8 the other shoe. As these two shoes are constructed in every 60 way the same, the description of one will suffice for both.

The body of the shoe is preferably made of cast iron, although any other suitable metal may be employed for the purpose. It 65 should also be understood that the shoe may be provided with any of the well known inserts in the wearing face, and also with any of the well known reinforcing members or elements located within the body of the shoe, 70 or at or adjacent to the back; in the drawings, however, I have illustrated a plain shoe, omitting these well known elements, as they form no part of the present invention. 75

On the back of the shoe are formed the guide lugs 9 and end stops 10, of the usual formation and dimensions, and in accordance with the M. C. B. standards. On the back, and about the center of the length 80 thereof, is also formed the attaching lug 11 provided with the usual opening 12 for the passage of the key 13 whereby to attach it to the brake head 14. On the back of the shoe are also formed the lugs or projections 85 15 located preferably on either side of the attaching lug 12, and on opposite sides of the longitudinal center of the shoe, each of these lugs being provided with an opening 16 extending through the same, for the passage of a nail, cotter pin, or other fastening device, as will be hereinafter explained. 90

While I have shown in the drawings but four of these lugs 15, it will be understood that any number may be used and positioned 95 or located as may be desired, these lugs, as will be hereafter understood, being employed for the purpose of securely holding the partially worn shoe to the face of a new or unworn shoe. In the wearing face of 100 the shoe are formed recesses 17 to receive and contain the guide lugs and end stops formed on the back of the adjacent shoe, and in the face of the shoe are also formed recesses 18 to receive and contain the lugs 15 or projections 105 on the back of the adjacent shoe, and also a recess 19 to receive and contain the attaching lug 11, the two shoes, when assembled, having the face of one shoe bearing against and resting upon the back 110 of the adjacent shoe as illustrated in Fig. 1, the projections on the back of one shoe fit-

ting in the corresponding recesses formed in the face of the other shoe.

- Through the end stops 10 are formed the openings 20 registering with holes or openings 21 formed in the body of the adjacent shoe when the parts are assembled as illustrated in Fig. 1, and in the body of the shoe, near the wearing face, are also formed the holes or openings 22 and 23, the holes 22 5 registering with the openings 16 formed in the lugs 15 when the parts are assembled, and the hole or opening 23 registering with an opening 24 extending through the attaching lug 11, so that when the parts have been 10 properly assembled as illustrated in Fig. 1, nails, cotter pins, or similar devices 25, may be passed through the openings 20 whereby to lock the two shoes together, Fig. 4 illustrating the nail or cotter pin passing 15 20 through the lugs 15 and through the body of the adjacent shoe, Fig. 5 showing a nail or cotter pin passing through the attaching lug and body of the adjacent shoe, and Fig. 6 a similar fastening device passing through 25 30 the end stop and opening in the body of the adjacent shoe for holding the two shoes together.

From the foregoing it will be understood that by reason of the location of the lugs 15 30 on either side of the attaching lug 11, and on opposite sides of the longitudinal center of the shoe, they in no wise interfere with the attaching key 13 employed for securing the shoe to the brake head; furthermore, that 35 the two shoes are positively and securely locked together at the center thereof, and also at points between the attaching lug and end stops, thus affording five different points or places at which the partially worn 40 shoe is locked or fastened to the unworn shoe. Furthermore, it will be understood that by reason of the construction and formation of this shoe, the two parts going to make up the complete interlocking shoe, 45 viz., the partially worn shoe and the unworn shoe, may be easily and readily assembled, and by the use of nails, cotter pins or similar devices, they may be readily and securely locked together without the necessity of employing special tools therefor. It will also 50

be understood that by increasing or decreasing the number of places at which the shoes are locked together, the use of reinforcing members, such as steel backs, expanded metal, etc., may be avoided, for 55 should the worn shoe become cracked or broken in service, it will remain fastened or locked to the unworn shoe, and with little or no danger of becoming separated therefrom.

What I claim is:—

1. An interlocking shoe comprising two shoes, a central key lug on the back of each shoe, an end stop at each end of said shoe, lugs formed on the back of each of said shoes and located between the central lug 65 and end stops, and on opposite sides of the longitudinal center of the shoe, said lugs being formed with transverse openings through the same, the wearing face of each of said shoes being provided with similarly 70 located recesses to receive the lugs on the back of a corresponding shoe, and each of said shoes being provided with transverse openings through the body and lugs, and pins fitting in said transverse openings 75 whereby to retain the two shoes in their assembled positions.

2. An interlocking shoe comprising two shoes, a central key lug formed on the back of each shoe, an end stop at each end of the 80 shoe, lugs formed on the back of each shoe between said key lug and end stops, and on the opposite sides of the longitudinal center of the shoe, each of said shoes being also formed with correspondingly located recesses in the wearing face thereof to receive 85 said lugs and end stops of the adjacent shoe, the bodies of each shoe, lugs and end stops, being provided with aligned transverse openings, and pins fitting in said transverse 90 openings and extending through the shoes whereby to retain the latter in their assembled positions.

Signed at Los Angeles, in the county of Los Angeles and State of California, this 95 tenth day of July A. D. 1914.

GARDINER W. CHIPLEY.
